BYRON B. MINNIUM, OF CHICAGO, ILLINOIS, ASSIGNOR, BY MESNE ASSIGNMENTS, TO STORY & CLARK RADIO CORP., OF CHICAGO, ILLINOIS, A CORPORATION OF DELAWARE

THERMIONIC AMPLIFIER SYSTEM

Application filed March 18, 1926. Serial No. 95,721.

This invention relates to radio receiving apparatus, and more particularly to apparatus of this character making use of radio frequency amplification with the agency of vacuum tubes and repeating coils.

In radio frequency amplifiers there occurs, unless means for preventing such occurrence are provided, what is known as feed-back or regeneration, due to the inherent capacity between the plate and grid of the vacuum tubes whereby the grid and plate circuits are coupled together in such a manner as to cause oscillation, as in any of the well-known oscillation generators. Such self-oscillation of the tube results in an unstable condition thereof and seriously interferes with the reception of signals, and oftentimes sets up undesirable noises in the receiver.

It is a general object of the present invention to provide a novel and improved means for preventing feed-back or self-oscillation in the vacuum tube of a radio frequency amplifier.

More particularly it is an object of this invention to eliminate self-oscillation and feed-back in radio frequency amplifiers by constructing each stage of the amplifier as a Wheatstone bridge, one arm of which includes the grid-to-plate capacity of the tube, and balancing this bridge so as to prevent a flow of current between the output and input circuits.

Other and further objects of the present invention will become more apparent to those skilled in the art as the description proceeds.

For a complete understanding of the invention, reference should be had to the accompanying drawings and the following specification, wherein is disclosed a single exemplary modification of the invention with the understanding, however, that various changes may be made thereon without departing from the spirit of the invention or the scope of the appended claim.

In said drawings:

Figure 1 is a diagram of radio receiving apparatus involving the principles of the invention; and

Figure 2 is a schematic arrangement of the

circuit of the amplifier showing the balanced Wheatstone bridge.

Referring first to Figure 1, there is shown a radio circuit or hook-up in which conventional symbols have been used throughout for the various parts, but a single stage of radio frequency and a detector being illustrated, although it is to be understood that any desirable number of radio frequency stages, each identical with the one disclosed, may be employed, and suitable audio-frequency amplifiers be added after the detector if a greater signal volume is required. The antenna 10 is connected to the ground thru a suitable primary coil 12 of the coupler or repeater 13. The secondary coil 14 of this coupler is tuned by means of the variable condenser 15, connected in shunt thereto, to resonance with the incoming signal. One end of the tuned circuit, comprising the secondary 14 and the condenser 15 is connected to the grid 16 of the conventional vacuum tube 17, the filament 18 of which is heated so as to give off electrons by means of the filament battery A, the current being controlled by the rheostat 19. The opposite end of the tuned circuit 14, 15, is connected to the negative side of the filament by means of the conductors 20 and 21, thus completing the so-called input or grid circuit of the tube.

The plate 22 of the tube is energized from the plate battery B through the conductor 23 and the choke coil 24, here illustrated as being provided with an iron core, although this is not necessary. This choke functions to keep the radio frequency currents out of the B battery circuit. The plate may be said to have a shunt connected current supply. A plate return to the filament for the radio frequency currents must therefore be provided. The conductor 25 connects the plate with the primary of the repeat coil 26, which couples the output of the radio frequency amplifier to the tuned circuit of the detector tube 27, as will be understood from the drawings. The primary of the repeat coil 26 is divided into two parts, 28 and 29, between which parts is connected the stopping condenser 30, of large capacity, its function being merely to prevent the flow of the B bat-

ter current directly back to the positive side of the A battery. Its capacity is so large that it offers no appreciable resistance to the flow of the radio frequency currents and therefore need not be considered as a part of the radio frequency circuit.

The circuit as described, is subject to self-oscillation owing to a tendency for radio frequency current to flow from the plate to the grid in the tube owing to the inherent capacity of these two elements. To counteract this flow, that end of the tuned input circuit opposite the grid is connected, by means of the wire 20 to the point X, which lies between the two sections 28 and 29 of the primary of the repeat coil 26. These sections are divided at such a point that a substantially neutralizing voltage will be applied to the point X commercially, a small variable balance, for it is difficult to exactly locate the point X commercially, a small variable condenser may be connected, as shown in dotted lines at 300, between the filament and grid, or if necessary, if the potential of the point X is too high, between the grid and plate. This condenser can be adjusted to give exact balance or neutralization, as it is sometimes termed.

In Figure 2, the various elements of Figure 30 1 involved in the radio frequency amplifier are arranged in the form of a Wheatstone bridge. The four points or junctions of the bridge are lettered respectively F, G, P and X; F representing the filament 18, G the grid 16, P the plate 22 and X the junction X of the two parts of the repeat coil 26. Between G and P, the small condenser 31 represents the grid-to-plate capacity of the tube. Between the points F and G, the small condenser 32 represents the capacity between the filament and grid in the tube. These condensers comprise two arms of the bridge and the other two are composed of the parts 28 and 29 of the primary of the repeat coil 26. The condenser 300 has been omitted, since, as explained, it forms no part of the radio frequency circuit. It will be seen that the tuned circuit of the repeat coil 13 is applied between the conjugate points G and X, and hence forms no part of the bridge. It will likewise be seen that the B battery and its choke are connected between opposite conjugate points of the bridge and that the secondary 33 of the repeat coil 26 is coupled to the arms 28 and 29 of the bridge in a balanced manner. This arrangement will disclose the inherent balance of the bridge and will clearly illustrate the means for preventing feedback or self-oscillation. It will be readily apparent that when the bridge is balanced by a proper co-relation of the condensers 32 and 31 and the coils 28 and 29, that any electrical disturbances occurring between the conjugate junctions F and P cannot have any effect on the potentials of the junctions G and X. Con-

versely, any changes in the electrical conditions of the points G and X, due to variation in the input circuit of the tube, cannot have any effect on the potentials of the points P and F. In this manner the grid and plate can be considered as electrically isolated, for the purpose of balance and the tube circuits are thus inherently balanced and stable.

The tuning circuit being connected to opposite points of the bridge does not, by its variation, affect the balance and the same may be said of the B battery circuit.

Having thus described the invention, what is claimed as new and desired to be secured by Letters Patent is:

Radio frequency receiving apparatus comprising in combination, a vacuum tube having a filament, a grid and a plate, an input inductance, an output inductance, and a source of plate supply, said elements being arranged in the form of a balanced Wheatstone bridge, the grid-to-plate capacity of the tube being in one arm of the bridge, the filament-to-grid capacity being in another arm, said output inductance being divided into two portions by a stopping condenser, each portion being in its allotted one of the two remaining arms of said bridge, with said stopping condenser in one inductive arm, and a secondary circuit coil inductively coupled to both parts of said output inductance.

In testimony whereof I hereunto affix my signature.

BYRON B. MINNIUM.
